WRINGER MOUNTING AND DRIVE FOR
WASHING MACHINES

Alvin C. McCord, Chicago, Ill., assignor, by mesne assignments, to McCord Radiator & Mfg. Co., Detroit, Mich., a corporation of Maine

Application October 5, 1931. Serial No. 566,997

4 Claims. (Cl. 68—32)

This invention relates to washing machines and more particularly to the mounting and the drive for the wringer mechanism thereof.

In my co-pending application Serial No. 566,996 filed October 5, 1931, I have disclosed and claimed a wringer mounting in which the wringer is swingable or adjustable with respect to the tub of the machine about an axis different from that through which power is applied to the wringer to operate the wringer rolls. The specific embodiment disclosed in that application includes a ring gear about the axis of which the wringer is adjustable, the shaft for rotating said gear extending through the same in offset or eccentric relation to the axis thereof.

In accordance with the present invention the wringer is adjustable about the axis of a gear, but the gearing arrangement is somewhat different from that disclosed in said other application.

In the present, as well as in the other application, I employ a reversible electric motor to operate the machine, and use a control switch for starting, stopping and reversing the motor to reverse the direction of rotation of the wringer rolls. In both cases, I also employ means in the drive to the wringer for disconnecting it therefrom when desired, such means in both cases being in clutch form.

In accordance with my present invention, I so arrange the clutch in the drive that the clutch and the control switch for the motor may be operated simultaneously from a common actuator. The advantage of this is that it simplifies the control of the machine and also insures releasing the wringer rolls from the torque of the motor before adjusting the wringer from one position to another, making a safety factor in that no opportunity is afforded for the wringer to be forcibly swung about to hit the operator as is possible in other machines.

Other and further objects of the invention will appear from the following specification taken in connection with the accompanying drawings, in which—

Fig. 1 is a side view of a washing machine embodying the features of my invention;

Fig. 2 is a vertical sectional view with parts in elevation, taken on line 2—2 of Fig. 1;

Fig. 2a shows the clutch construction to be hereinafter described;

Fig. 3 is a horizontal sectional view taken on line 3—3 of Fig. 2 to show certain details of construction;

Fig. 4 is a horizontal sectional view taken on line 4—4 of Fig. 2;

Fig. 5 is a similar view taken on line 5—5 of Fig. 2;

Fig. 6 is a side view, with parts in section, of the control switch and clutch actuator; and

Fig. 7 shows a stop pin for such parts to be hereinafter described.

In the drawings, 1 indicates the tub of the machine arranged on a support 2 having legs 3. The tub 1 is of the upwardly opening type and is provided with a removable lid or cover (not shown). Arranged within the tub 1 is an agitator 4 disposed to be oscillated about a vertical axis as provided by an upright spindle 5 (Fig. 5) extending centrally into the tub through its bottom wall. The agitator 4 is carried by and mounted on the upper end of said spindle as in machines of this character.

Arranged exterior of the tub 1 at one side thereof is an upright driving shaft for the wringer mechanism 6, the latter being located above the tub and mounted for swinging adjustment with respect thereto. The shaft referred to comprises upper and lower aligned sections 7, 8, the latter being journaled in a casing 9 below the tub and enclosing the drive for the machine. The upper shaft 7 is located in a tubular housing 10 secured to the side of the tub through a bracket 11. The lower end of the housing joins with a tubular portion 12 provided on the casing 9 for the lower shaft 8, as shown in Figs. 1 and 2. A sleeve 13 maintains the opposed ends of shaft sections 7, 8 in alignment, the sleeve being fixed, as by a pin, to section 8. Section 7 has its lower end rotatably mounted in said sleeve, the latter forming one of the members of the clutch and having clutch teeth 14 at its upper end.

Bracket 11 has an upwardly extending tubular portion 15 provided at its upper end, above the tub 1, with an outwardly projecting flange 16 forming a seat for the supporting fixture for the wringer mechanism. Said fixture is in the form of a casing having upper and lower sections 17, 18, the latter having a depending tubular portion 19 bearing on said seat. Housing 10 fits into tubular portion 19 and provides a guide and support therefor when assembling the parts. The upper end of shaft 7 terminates in the tubular portion 19 and is connected by a sleeve 19a with the lower end of a stub shaft 20 journaled in the bottom wall of section 18. There is a slip, but non-rotative connection, between shaft 20 and coupling 19a to permit assembling and disassembling of the parts.

A gear pinion 21 is fixed to the upper end of shaft 20 within casing section 18 and meshes 110

- with a gear 22 having a hub 23 on its underside rotatably seated in a recess 24 formed in the bottom wall of the section 18. A bevel gear 25 is supported by gear 22 on its upper side, being fixed for rotation therewith through a central boss 26 on the underside of the bevel gear fitting in a recess in the carrying gear. A bevel gear 27 is in mesh with bevel gear 25 and is fixed to a shaft 28 connected by a coupling sleeve 29 to the adjacent end of a shaft 30 of the lower roll 31 of the wringer mechanism. Shaft 28 is journaled in a lug or web section 32 on the upper section 17 of the gear casing. The wringer mechanism 6, through its supporting frame 34, is attached to this web by fastening members 33. The upper roll 35 of the wringer mechanism, is journaled in the frame 34, and is yieldably pressed against the lower roll by the usual spring tension as employed in wringer constructions.
- The upper section 17 of the gear casing is rotatably mounted on the lower section 18 for turning movement about the axis of the gear assembly 22-25, such axis being offset to one side of the main drive as provided by shafts 7 and 8. The wringer mechanism 6 being carried by the upper section 17 may be swung or adjusted about this axis which is different from the axis through which power is supplied to the wringer for rotating its rolls. The mounting for the upper section 17 comprises an outwardly projecting flange 36 at the upper end of the lower section 18 and a cooperating rib or web 37 adjacent the lower end of the upper section 17, as shown in Fig. 2. The lower marginal portion 38 of the upper section 17 fits into the lower section at the flange 36 and guides and centers the sections for relative movement. The construction also prevents the lubricant contained in the casing from leaking out at the joint.
- To hold the wringer mechanism 6 in any of its different positions of adjustment, I provide a latch mechanism comprising the web 37 with a plurality of circumferentially spaced notches 39, as shown in Fig. 4. These notches are preferably arranged in two groups with a number of notches in each group, as for example three, as shown in Fig. 4. The groups are diametrically disposed and thus are on opposite sides of section 17. Inasmuch as the wringer mechanism requires only a few positions of adjustment, either when over the tub or when exterior thereto, as shown by full and dotted lines, respectively, in Fig. 4, I need only provide two groups of notches in the rib or web 37, as shown in that figure.
- A manually operable latch member 40 is pivoted or fulcrumed at 41 on the lower section 18 of the gear casing, preferably at the tub side of the assembly, for engaging the notches 39. Latch member 40 is pivoted between lugs 42 on the outside of section 18 and the space between the lugs is continued upward through the flange 36 providing a slot 43 to accommodate the upper end of the latch member. The upper end of the latter is shaped to fit in any one of the notches 39 and is movable into and out of the same through a slot 44 in a ring 45 fitted over the upper and outer sides of the web 37 and secured to the flange 36 by screws 46. Ring 45 thus holds the casing sections 17, 18 in assembled relation.
- A coil spring 47 is employed for normally moving the latch member 40 in a direction for its upper end to engage in any one of the notches 39 when a notch is brought opposite the latch member. This spring is carried by the lower section 18 between lugs 42, and expands outwardly

against the inner side of the latch member. To release the latch member from a notch 39, the lower end of the latch member is pressed inward, whereupon the wringer mechanism 6 is free for adjustment.

To reverse the direction of rotation of the wringer rolls, I employ a reversible electric motor 48 located beneath the tub of the machine and carried by the base or support 2. The motor is preferably mounted with its armature shaft 49 horizontal and which by a coupling 50 is connected with a drive shaft 51. The latter is provided with a worm 52 meshing with a worm gear 53 located in the housing 9. Gear 53 is fixed to a shaft 54 journaled in the bottom wall of housing 9 in line with shaft 8, as shown in Fig. 1. Gear 53 has a crank pin 55 connected with a crank-arm 56 fixed to the lower end of shaft 8. For actuating spindle 5 from gear 53, a rod 57 is pivoted at one end to the pin 55 and has rack teeth 58 adjacent its other end meshing with a pinion 59 fixed to the spindle 5, as shown in Fig. 5. A spring pressed plunger 60 is mounted in the housing 9 to guide and hold the rod 57 in mesh with the pinion 59.

The clutch for the wringer drive comprises clutch members 61, 62. The member 61 is fixed to shaft 7, as by a pin or key, while member 62 is slidably and rotatably mounted on shaft 7 between member 61 and sleeve 13. Member 62 is provided with clutch teeth 63 and 64 at its opposite ends, the teeth 63 being relatively long so as to retain engagement with the teeth 65 on member 61 in all shifted positions of member 62, as illustrated in Fig. 2a. By this arrangement, member 62 is rotated at all times with member 61 and when shifted to have its teeth 64 in engagement with the teeth 14 on sleeve 13, shaft 7 and the connected wringer roll 31 will be rotated from shaft 8 in the operation of the motor 48.

Clutch member 62 is provided with an annular groove 66 engaged by a fork or yoke 67 fixed to a slide rod 68 arranged parallel to shaft 7 and disposed at one side of the same in a casing 69 which forms a housing for the clutch mechanism and is a continuation of the lower end of the tubular casing 10 for shaft 7. Rod 68 extends above the upper end of casing 69 and is connected with an arm 70 fastened to the lower end of a vertically disposed rod 71 slidably mounted in a bracket 72 fixed to the tube 10 and extending to one side thereof, as shown in Figs. 1 and 2. Rod 71 is pivotally connected at its upper end to a depending lug 73 on an eccentric strap 74 on an eccentric 75 located adjacent the bracket 11 at one side thereof, as shown. Eccentric 75 is mounted on the turn button 76 of a control switch 77 for the motor 48, as shown in Figs. 6 and 7. Eccentric 75 is provided with an outwardly projecting lug 78 in line with the axis of the switch button 76. The lug 78 forms a support for a handle member 79 connected with the lug by fulcrum pin 80 arranged transverse to the axis of the lug so that the handle 79 may be moved toward and from the eccentric for the purposes to presently appear. This movement of the handle is permitted by the widened recess or slot 81 provided therein for the lug.

Switch 77 is of the desired six pole type to stop, start and reverse the motor 48. To reverse the motor, the current in the starting winding must be reversed in relation to the running winding. This can be accomplished with a four pole switch, but the two additional poles are neces-

sary to start and stop the motor. Inasmuch as the switch mechanism can be procured on the market, I need not further describe it.

To hold the eccentric 75 on the switch button 76, I provide a fixture in the form of a sheet metal strap 82 fastened at one end, as by screw 83, to the outer side of the bracket 11. The strap 82 is so formed as to extend over the outer side of the eccentric 75 and has an opening therein to accommodate the eccentric lug 78, as shown in Fig. 6. The other end of the strap continues down on the outer side of the switch casing 77 and is connected by one or more screws 84 with a second strap 85 which continues down to the ear 86 on the bracket 11 and is fastened thereto by one of the screws 87 which fastens the bracket 11 to the tub 1. The switch 77 is secured at its base to the adjacent ear of the bracket 11 by its own bolts.

When the washing machine is not in operation, the handle member 79 is in the position shown in Fig. 1, extending upward above the switch button 76. The switch contacts are open at this time and no current is supplied to the motor 48.

To start the motor, the handle 79 is turned into a horizontal position to either side of the upright or vertical portion shown in Fig. 1. Turning the handle to one side, as away from the bracket 11, furnishes current to the motor 48 in a manner to operate it in one direction. Turning the handle to the other side, as toward the bracket, causes the motor to be operated in the opposite or reverse direction. These positions for the handle 79 are marked in Fig. 1 with the dot and dash lines B, B'. The switch 77 is of such construction that its spring snaps the contacts into closed position as the handle 79 reaches either positions B or B'. The spring snaps the contacts open when the handle reaches a vertical position, either above or below the strap 82. Moving the handle 79 into either horizontal position B or B' does not shift the eccentric 75 far enough to shift clutch member 62 into clutched engagement with the sleeve 13 with the result that no power is supplied to the wringer mechanism 6 at this time. Power, however, is furnished to the spindle 5 and the agitator 4 is oscillated back and forth in tub 1.

To connect the wringer mechanism with the source of power, it is necessary to move the handle 79 into either of the inclined positions C or C' below the positions B and B'. In position C, the wringer rolls will be turned in one direction, while in position C' they will turn in reverse. This is due to the reversing of the motor 48 as the handle passed through positions B, B'. Inasmuch as it requires a 90 degree movement for the switch button 76 to separate the contacts of the switch to cut off the current to the motor, I can still retain the motor in operation by moving the handle 79 to the midway positions C or C'. The extent of movement of the handle into either of these positions is sufficient to shift member 62 into clutched engagement with the sleeve 13 and thus connect shaft 7 to shaft 8.

Changing the direction of rotation of the wringer rolls by the use of a reversible electric motor avoids the use of a reversing clutch or other reversing mechanism in the driving connection between shaft 7 and the wringer rolls and thus simplifies the driving connection between such parts. Moreover, the elimination of a reversing clutch in the gear housing 17-18, enables the wringer mounting to be made with an adjustment for the wringer about an axis different from that

through which power is supplied to the wringer rolls.

To retain the handle 79 in either of its positions C or C', I provide the handle at one end with an inwardly projecting lug 88 to enter holes or notches 89, 90 in the strap 82 above the horizontal positions B, B' and on opposite sides of the vertical position shown in Fig. 1. The handle is yieldingly pressed toward the strap by a light coil spring 91 disposed on the inner side of the handle in a recess or socket formed therein as shown in Fig. 6. The end of the spring beyond the handle seats against a disc 92 which encircles the eccentric lug 78 and is rotated with the handle. The disc has a notch 93 through which the lug of the handle extends to connect the disc at all times with the handle and thus provides a bearing or support for the spring. To prevent the handle 79 from being turned to far beyond positions C or C', so that the spring of the switch cannot open the switch contacts, and thus stop the motor, I provide the strap 82 on its front side with a stop pin 94 arranged in the path of movement of the lug 88, as shown in Fig. 7. The handle 79 is pushed inward 100 against the spring 91 to release its lug 88 from the notches 89, 90, whereupon the handle may be turned back to positions B or B' or back to starting position, as shown in Fig. 1 for cutting off the current to the motor. At this time the 105 lug 88 of the handle rides against the outer side of the bracket 82, the spring 91 serving to hold the lug against the bracket. The tension of the spring in the switch mechanism is sufficient to hold the handle in either positions B or B' and thus no other means are required for the purpose. When the handle is in position with the switch off, as in Fig. 1, the spring 91 in normally projecting the hand grasping portion of the handle away from the bracket plate 82, will hold the 110 handle out of the path of the stop 94 and thus the handle may be turned into either of the positions B or B' or continued on to C or C'.

To hold the lower section 18 of the gear casing stationary, that is against rotary movement, I connect the depending portion 19 of the section with the bracket 11. This connection is illustrated in Fig. 3, and as shown comprises a pin 95. The pin is carried by an outwardly extending lug 96 at the lower end of the depending portion 19 and is received in an aperture or recess in a similarly arranged lug 97 on the bracket 11 at the upper end of its tubular section 15, preferably on the flange 16. As shown in Fig. 3, this flange is slightly larger in diameter than the 130 lower end of the portion 19 so that the pin 95 may ride on the upper surface of the flange 16 when adjusting the parts to register the pin with its receiving socket in the flange.

The mechanism shown and described is simple 135 in construction and effective in operation. Moreover, it can readily and easily be assembled or disassembled and with the pin and socket connection between bracket 11 and casing 18, the entire wringer mechanism of the machine may 140 be applied to or be removed from the machine as a unit, which it will be noted carries the latch mechanism for the wringer. There is only one control member for the machine and that is the handle 79. This member not only actuates the 145 switch 77 whereby the motor 48 may be started, stopped and reversed, but actuates the clutch for connecting the wringer with the source of power whenever desired. The clutch permits the wringer rolls to be completely disconnected from 150

the torque of the motor when swinging or adjusting the wringer to its various positions, and thus there is no opportunity afforded for the torque of the motor to forcibly throw the wringer against 5 the operator, as when the wringer rolls remain under the possible influence of the motor's torque while adjusting the wringer.

The details of construction and arrangement of parts may be variously changed and modified 10 without departing from the spirit and scope of my invention, except as pointed out in the appended 15 claims.

I claim as my invention:

1. In a washing machine, a roll wringer therefor, a main driving shaft for the wringer rolls, 15 a gear completely offset to one side of said shaft, said shaft and said gear being disposed to rotate about substantially parallel vertical axes, a driving connection from the shaft to the wringer rolls 20 through said gear, and means providing a mounting for the wringer whereby the latter may be adjusted about the axis of said offset gear and for maintaining the driving connection constantly engaged while swinging the wringer about the 25 axis of the offset gear and in all positions of adjustment of the wringer with respect to said gear.

2. In a washing machine, a roll wringer therefor, a main driving shaft for the wringer rolls, 30 two meshing gears disposed in the plane of each other and arranged to rotate about substantially parallel vertical axes, one gear being coupled to the shaft and in alignment therewith, and the other gear completely offset to one side of 35 the shaft, a driving connection from the offset gear to the wringer rolls, and means providing a mounting for the wringer whereby the latter may be adjusted about the axis of the offset gear and for maintaining the gears constantly 40 enmeshed while swinging the wringer about the axis of the offset gear and in all positions of the adjustment of the wringer with respect to said gear.

3. In a washing machine, a roll wringer therefor, a main driving shaft for the wringer rolls, two pairs of meshing gears providing a driving connection from the shaft to the wringer rolls, the gears of one pair being spur gears disposed in the same horizontal plane and arranged to rotate about substantially parallel vertical axes, one gear of said pair being coupled to and in alignment with said shaft and the other gear of said pair being completely offset to one side of the shaft, the gears of the other pair being beveled with one connected with the wringer rolls and the other to the offset gear, and means providing a mounting for the wringer whereby the latter may be adjusted about the axis of the offset gear and for maintaining the gears constantly enmeshed while swinging the wringer about the axis of the offset gear and in all positions of adjustment of the wringer with respect to said gear.

4. In a washing machine, a roll wringer therefor, a gearing for actuating the wringer rolls, a casing providing a housing for the gearing and a mounting for the wringer, said casing being divided horizontally into a lower stationary section and an upper rotatable section, the latter carrying the wringer and having a rotative connection with the lower section by fitting within the same and having an exterior flange seating on the upper edge of the lower section, a latch member carried by the lower section and engageable with notches in said flange for releasably holding the upper section and attached wringer against rotative adjustment with respect to the lower section, and a clamping ring secured to the lower section in overlapping relation with said flange for holding the section together, said ring having a slot whereby the latch member may extend therethrough to engage the notches in the flange.
